Primary Examiner — Lauren R Calve(74) *Attorney, Agent, or Firm* — Luedeka Neely Group, PC(57) **CLAIM**

The ornamental design for a folding hanger, as shown and described.

DESCRIPTION

FIG. 1 is a perspective view of a folding hanger of our new design in a folded orientation.

FIG. 2 is a right side view thereof.

FIG. 3 is a left side view thereof.

FIG. 4 is a front plan view thereof.

FIG. 5 is a bottom view thereof.

FIG. 6 is a top view thereof.

FIG. 7 is a rear plan view thereof.

FIG. 8 is a perspective view thereof as the folding hanger is being transitioned from the folded orientation to an unfolded orientation; and,

FIG. 9 is a perspective view thereof in the unfolded orientation.
